UNITED STATES PATENT OFFICE.

GEORGE CLAUSING, OF PORTSMOUTH, OHIO, ASSIGNOR TO THE VULCAN BOX TOE
PROCESS CO., OF PORTSMOUTH, OHIO, A CORPORATION OF OHIO.

LAST.

1,107,655.

Specification of Letters Patent. Patented Aug. 18, 1914.

Application filed February 12, 1914. Serial No. 818,353.

To all whom it may concern:

Be it known that I, GEORGE CLAUSING, a citizen of the United States, residing in the city of Portsmouth, in the county of Scioto 5 and State of Ohio, have invented certain new and useful Improvements in Lasts, (Case H,) of which the following is a specification.

The object of the invention is to produce a 10 simple, strong, practical and rigid last which can be readily broken or flexed so as to facilitate the removal of the last from the shoe and so that the shoe will not be marred, broken or pulled out of shape during the removal of the last from the shoe.

According to the present invention a last is constructed so that it will comprise a forward or toe part and a rear or heel part which are provided between them with main 20 bearing pins or members that extend transversely to the last. The heel and toe parts are connected together by a longitudinally extending rod or link, one end of which rod is pivotally connected to the toe part and 25 the other end of which is pivotally connected to the heel part. When this link occupies its lower position the heel and toe parts occupy their unbroken position relative to each other. This link is normally pressed down- 30 wardly by a compression spring which is located in the toe part above said link.

As showing a specific embodiment of the invention reference is made to the drawing forming a part of this specification and in 35 which,—

Figure 1 is a vertically and longitudinally extending sectional view of the last. In this figure the full lines indicate the position of the parts when in extended or unbroken 40 position, while the broken lines indicate the position of the heel part relative to the toe part when the last is broken or flexed. Fig. 2 is a plan view, partially in section. This figure is a view taken on the line 2—2 of Fig. 1, looking in the direction of the arrows. Fig. 3 is a transverse sectional view taken on the line 3—3 of Fig. 1 looking in the direction of the arrows. Fig. 4 is a sectional view of the toe part showing the manner in which the link receiving opening may 45 be formed.

The last A comprises the forward or toe part B and the rear or heel part C. In the construction of the last the toe and heel

parts are preferably formed from a single 55 piece of wood and are integrally connected together. They are subsequently separated by transversely sawing as along the line *d—d* and a V shaped portion *d*, *e* and *f* is sawed out and removed from the last whereby the 60 heel part can move from the position indicated by the full lines in Fig. 1 to the position indicated by the dotted lines in order to break, flex or shorten the last. At the junction of the saw cuts indicated by the line *d—d* 65 on one hand and by the line *e—f* on the other, there is located the main bearing members or pivot pins F—F. These pins are preferably secured as by the pins or nails *f—f* to the toe part of the last. It will be 70 manifest however that in some constructions these main bearing members instead of being independent from may be formed integral with and of the same material as the toe part, for instance, since all that is necessary 75 in the last construction is to have circular bearing surface on one of the parts which can fit into the curved recess portions on the other part.

After the heel and toe parts have been 80 separated by transversely sawing along the line *d—d*, they are each provided with openings for receiving the connecting link or bar "G." These openings may be formed by boring in each part a couple of openings 85 *g—g'*, inclined to each other. These bored openings run into each other and the material, as *g''*, between them is subsequently removed, thus forming the triangular shaped opening *h* in the toe part and the 90 opening *i* in the heel part. This connecting link, which is shown of circular cross section, is pivotally connected to the toe part by the pin or rivet *j* and to the heel part by pin or rivet *k*. One of the openings 95 through which one of the pins or rivets pass is elongated, as at *p'*, to permit the heel and toe parts to be moved to full flexed position when desired. This link is arranged so that the line through the center of the 100 pins or pivots *j* and *k* is located below the center of the axis of the main bearing pins F when the last is unbroken, but this link swings to the dotted position shown in Fig. 1 so that the line passing through said pivot 105 centers is located above the axis of the main bearing pins F when the heel part occupies the position indicated by the broken

lines, or namely, when the heel and toe parts occupy the full flexed or broken position. The toe part is also provided with the vertically extending bored opening *l* in which there is located the spring means *M* that comprises the compression spring *m*, and the spring cap *n* that engages the connecting link *G* at or adjacent to the central portion of the link. This spring, as will be observed from the drawing, is located above the connecting link and normally presses against the latter, thus tending to force the last parts toward unbroken position and also tending to maintain said last parts in said unbroken position when they are in said position. The link *G* serves to connect and hold the toe and heel parts together and as the central portion of this link is engaged by the spring means *M*, the latter tend to very effectively force the link downwardly and thus securely maintain the heel and toe parts in unbroken position and in firm engagement with each other.

From the inspection of Fig. 1 it will be noted that the saw cut *d*—*d* extends the full length of the forward transversely extending face of the heel part and that the main bearing pins *F* are shown as being secured to the toe part. The recess *f'* in the heel part is semi-circular, thus affording a very substantial bearing area between the heel part and the main bearing pins or members. This is quite important as the wear tends to take place between the bearing pins or members and the member which moves relative to the bearing pins or members. In other words, it will be seen that the large bearing area is on the part that moves relative to the bearing pins and that there is less area between the bearing pins and the member to which they are secured.

The improvements herein set forth are not limited to the precise construction and arrangement shown and described and may be embodied in various forms and modifications without departing from the spirit and scope of the invention.

I claim as my invention:

1. A last having a toe part, a heel part, a connecting link between said parts and a compression spring engaging said link, said last having the heel part and toe part provided between them with bearing members which permit the heel part to swing from extended position to broken position relative to the toe part, said connecting link being pivotally connected at one end to the toe part and at the other end to the heel part, said compression spring being located in the toe part and engaging the upper portion of the link so as to continuously press said link downwardly.

2. A last having a toe part, a heel part, a link pivotally connected to each of said parts, and a compression spring located above said link for forcing the latter toward lower position, the last being provided with transversely extending main bearing pins and the link being arranged so that a line passing through the pivotal connections of the link to the last parts is located below the axis of the main bearing pins when the last parts are in extended or unbroken position but so that said line is located above the axis of the main bearing pins when the last parts are in broken or shortened position.

3. A last comprising heel and toe parts having provided between them transversely extending main bearing pins, a link pivotally connected at its forward end to the toe part and at its rear end to the heel part, and a substantially vertically extending spring means located in the toe part and normally pressing downwardly against the link to maintain the heel and toe parts in extended position.

This specification signed and witnessed this 9th day of February, A. D. 1914.

GEORGE CLAUSING.
